SYRINGE HOLDER

Hyla F. Maynes, Miami, Fla., assignor of one-half
to Emma C. Maynes, Miami, Fla.

Application October 18, 1945, Serial No. 623,085

18 Claims. (Cl. 128—218)

1

This invention relates to surgical syringes and particularly to means for facilitating the use of such syringes.

The device of the present invention is intended for use with syringes in various kinds of hypodermic injections or for the withdrawal of blood or other physiological specimens. Various devices of the prior art aim at facilitating the use of hypodermic and other surgical syringes but none of them fulfills the objects of the present invention.

According to the present invention syringe holders are provided which are fully automatic in operation once a device is placed in position for use and is released for operation. Further, means are provided whereby the positioning of the device relative to the portion of the patient's body to be acted upon may be readily established and positively maintained, despite any natural unsteadiness or disturbing reflexes on the part of the patient or the operator.

Further, the syringe holders of the present invention are characterized by the fact that syringes may be associated therewith by direct relating lateral movement of syringe and holder whereby the likelihood of damage to the syringe needle is virtually eliminated. In the prior art holders are usually so arranged that a syringe must be threaded into the holder axially in a manner which makes it difficult to prevent accidental contact of the needle with portions of the holder during assembly of the syringe and holder.

In addition, the device of the present invention is characterized by the fact that the movement of the syringe to insert the needle is effected by an actuator which engages and presses the syringe plunger to slide the syringe cylinder bodily along a stationary trough, so that the liquid in the syringe cylinder may act as a dash-pot during the sliding movement of the syringe along the trough. This sliding movement is arrested, after insertion of the needle, by a stop for the syringe cylinder, whereupon continued pressure of the actuator against the plunger acts to inject the dose through the needle. The above-mentioned relative lateral movement of syringe and holder, to associate or assemble them, is enabled by reason of the stationary trough edges being spaced apart sufficiently to receive the syringe between them, so that the syringe can be easily, 50 inserted or dropped into the trough.

Devices constructed according to the present invention further provide means whereby they may readily and repetitiously be set to properly receive and accommodate a syringe set for a pre-

2

determined dosage or capacity, or, in other form, to automatically operate the syringe according to a predetermined dose setting of the holder. The automatic operation of the device of the present invention assures relative uniformity in the rate of injection or extraction not attainable in the manual control and operation upon which the art presently relies.

In one of the several forms of the invention 10 illustrated and described herein to exemplify the principles of the invention the entire operation of preparing the syringe, taking up a dose, inserting the needle, administering the dose and withdrawing the needle from the patient is accomplished by manipulation of the holder.

Other objects and advantages of the devices constructed and used in accordance with the underlying principles of the present invention will appear to those skilled in the arts involved 20 from a consideration of the following specification and the accompanying drawing, wherein several specific practical embodiments of the invention are set forth by way of example. The scope of the present invention, however, is not limited 25 to the exemplary forms illustrated, or in any other way excepting as defined in the appended claims.

In the drawings:

Fig. 1 is an elevational view of one form of the holder of the present invention with a syringe 30 associated therewith and ready for use;

Fig. 2 is another elevational view taken at right angles to Fig. 1 and with a portion of the holder broken away for added clearness;

Fig. 3 is a longitudinal cross sectional view 35 viewed similarly to Fig. 1;

Fig. 4 is a view similar to Fig. 3 but at a later stage of operation;

Fig. 5 is another view similar to Fig. 3 but at the final stage of operation;

Fig. 6 is a transverse cross sectional view on the line 6—6 of Fig. 1;

Fig. 7 is a transverse cross sectional view on the line 7—7 of Fig. 1;

Fig. 8 is a transverse cross sectional view on the line 8—8 of Fig. 1;

Fig. 9 is a transverse cross sectional view taken on the same plane as Fig. 8 but looking in the opposite direction and showing a syringe in the process of assembly in the holder;

Fig. 10 is a view similar to Fig. 9 but with the syringe in final position of assembly in the holder;

Fig. 11 is a detailed elevational view of the syringe operating plunger of the device of Figs. 1 through 10;

Fig. 12 is a longitudinal cross-sectional view

3

of another form of the holder of the present invention;

Fig. 13 is a transverse cross-sectional view on the line 13—13 of Fig. 12;

Fig. 14 is an elevational view of still another form of the device of the present invention;

Fig. 16 is a transverse cross sectional view on the line 16—16 of Fig. 14;

Fig. 17 is a longitudinal cross sectional view of the device of the Figs. 14 through 16 viewed at right angles to Fig. 14;

Fig. 18 is a longitudinal cross sectional view of a further embodiment of the principles of the present invention;

Fig. 19 is a fragmentary elevational view of the medial portion of the embodiment of Fig. 18 viewed at right angles to Fig. 18; and

Fig. 20 is a transverse cross sectional view on the line 20—20 of Fig. 18.

Throughout the several figures of the drawings like characters of reference denote like parts and referring first to the embodiment of the invention illustrated in Figs. 1 through 11, the numeral 10 designates generally the main body portion or holder of the device comprising a barrel portion 11, a shank 12 extending longitudinally from one side thereof, and a generally cylindrical end portion 13. As appears from Figs. 2 through 5, the conventional syringe, which the several holders set forth by way of example are designed to accommodate, is designated 14 generally and comprises a cylinder portion 16, a plunger 17 having a head 18, and a needle 19. In one form of surgical syringe in common use, the plunger end of the cylinder portion 16 has an enlarged annular flange or collar 20 which is flattened at opposite sides as at 21.

Conventional syringes of the kind referred to herein by way of example have annular beads at the needle end of the syringe cylinder as indicated at 22 in Figs. 2 through 5. To simplify the assembly of a syringe in the holder of Figs. 1 through 11 opposed flats 23 are formed on the bead 22, as by grinding conventional syringes. Obviously, syringes intended for use or for possible use in a holder of the form being described may be provided with the flats 23 in their initial manufacture. The flats 23 are in registry with the flats 21 of collar 20 at the other end of the syringe cylinder.

The walls of the barrel portion 11 and the cylindrical end portions 13 have longitudinal lateral openings 24 and 25, respectively, which, with the connecting shank portion 12, form a continuous lateral opening which freely receives the syringe, regardless of the degree to which the plunger 17 may be withdrawn. In other words, the shank 12, the end portion 13, and the barrel portion 11, because of the longitudinal lateral openings 24 and 25, form a stationary trough for engaging and supporting the syringe cylinder and providing a guide for longitudinal movement of the cylinder along the trough, the space between the trough edges being sufficiently wide to receive the syringe. When the holder is constructed for use with a syringe having a flattened head portion and a flattened bead, as described above, the opening 24 is made wide enough to receive the flange or collar 20 across flats 21, as is shown clearly in Fig. 9, and the opening 25 is made just wide enough to receive bead 22 across the flats 23. Each set of diametrically opposed flats 21 and 23 provides the syringe cylinder with a

4

generally rectangular cross-section, the smaller dimension of which is less than the width of the space between the opposed edges of the corresponding part of the trough, while the larger dimension is greater than this width. The syringe is assembled in the position shown in Fig. 9 and is then rotated a quarter turn to the position of Fig. 10. In such rotated position collar 20 and bead 22 prevent dislodgment of the syringe from the holder.

As shown in Fig. 3 the end of cylindrical end portion 13 is reduced and threaded to receive a cap 28 having an apertured end wall 29. The end wall 29 comprises an anvil or foot which is placed against the skin of a patient with the parts in the position illustrated in Fig. 3. It will be noted that cap 28 has a lateral opening 30 which forms a continuation of lateral opening 25 and permits the syringe to be inserted in the holder by direct lateral movement. The relative longitudinal position of cap 28 may be adjusted by reason of its threaded connection with end portion 13. Further, the lateral openings 25 and 30 make possible quick assembly of cap 28 on end portion 13 without threading the cap on from the end. One edge of portion 13 adjacent opening 25 is introduced into opening 30 by direct lateral movement in any desired relative longitudinal position and the parts are then rotated relative to each other a partial rotation until the openings 25 and 30 are in alignment and the threads in engagement.

The mechanism for releasing and automatically operating the device with the holder firmly supported in body contacting position will now be described. An operating element or actuator 35 of tubular form has an end wall 36 and is disposed for relative axial movement in barrel 11, that is, along the trough 11, 12, 13. End wall 36 of operating element 35 receives a screw 37 having a head portion 38 of resilient cushioning material for abutting engagement with head 18 of syringe plunger 17.

In the present embodiment a cap 39 threads into the outer end of barrel 11 and a compression coil spring 40 is confined between end wall 36 of operating element 35 and the inner face of cap 39. Spring 40 normally urges operating element 35 to the left as viewed in Figs. 1 through 4 but means are provided for retaining the operating member in various withdrawn positions against the resilient urge of spring 40. The exterior of operating element 35 is provided with a series of circularly extending ratchet teeth 44 as appears best from the detail view, Fig. 11, and a detaining pawl 45 is pivoted to the barrel 11 by means of torsion spring hinge 46 which normally urges the pawl in a counterclockwise direction as viewed in Figs. 3 through 5. An extension 50 of pawl 45 comprises a manually engageable release lever and includes a pad or projection 51 which may extend through a lateral opening in the wall of barrel 11 for frictional braking engagement with the surface of operating element 35, as shown in Fig. 4.

Referring to Fig. 3, a manually adjustable rod 56 may be employed as a stop to readily position operating member 35 to set the holder for receiving a syringe containing a predetermined dose. Rod 56 is supported in cap 39 which has an inward tubular extension 57, and rod 56 threads into the extension as at 58, so that the threaded portion constitutes an adjustment member connected to stop 56 by which it may be axially adjusted relative to barrel 11. In Fig. 3 rod 56 is

shown adjusted to provide for a dose of 10 units, and operating element 35 has been manually pushed to the right until screw 37 abuts the inner end of rod 56, thus automatically determining the initial position of operating element 35.

With the operating element so positioned the syringe 16 may merely be inserted in the manner previously described and plunger head 18 will be in contact with or very close to padded head 38 of screw 37. This guards against the operating element striking against the syringe plunger with impact which might injure the syringe. It will be noted from Figs. 1 and 2, particularly the latter, that barrel 11 of the holder has opposed ears 59 formed inwardly to serve as a stop which limits movement of the operating member 35 to the left as shown in Figs. 1 and 2. The end of operating member 35 will meet ears 59 when the parts reach the position shown in Fig. 5.

With the parts in the position of Fig. 3, the operator of the device, whether it be the patient or another person, places the cap 28 against the patient's skin at any desired angle and, holding the barrel firmly in fixed position, presses release lever 50 which removes pawl 45 from the ratchet teeth of operating element 35 and the force of spring 40 moves syringe 16 bodily until its collar 20 abuts U-shaped washer 60 which may be of resilient material, the rear face of the washer thus serving as a stop for the syringe cylinder to limit its forward sliding movement in the stationary trough. The washer 60 is shaped at its inner portion for sliding frictional engagement with the periphery of the syringe cylinder (Fig. 2), so that this inner portion of the washer constitutes a restraining member serving as a yieldable brake on cylinder 16 of the syringe, holding it against unintended lengthwise movement. The initial movement of operating element 35 brings the parts to the position of Fig. 4 where the needle is properly inserted in the patient. The needle inserting movement is relatively rapid and in the embodiment now being described depends upon the dash pot action of the syringe, since entry of the plunger 17 into the syringe cannot be rapidly effected because of the restricted orifice of needle 19.

After the parts reach the position of Fig. 4, operating element 35 continues to bear against head 18 of plunger 17 and the contents of the syringe are expelled through the orifice of needle 19 until the syringe is empty. The action of spring 40 may result in a too rapid expulsion of the contents of the syringe, but this rate is readily and simply controlled by pressure of the operator's finger on release lever 50 which engages projection 51 against the barrel 11 with any desired degree of pressure, thus providing a manually controlled brake for slowing the action of the operating element 35 to any desired degree. In this alternative, the rate of expulsion may be slowed and controlled by direct application of the thumb or finger of the user to the operator through opening 24, the thumb or finger engaging against operator 35 at about the point designated A in Figs. 1 and 2. Fig. 5 shows the position of parts when the syringe plunger has fully entered syringe 16, and the device may then be removed to withdraw the needle from the patient.

It will be noted that shank 12 is slightly narrower than the diameter of the cylinder portion of the syringe. This facilitates ready manual grasping of the syringe without interference on

the part of shank 12, both in assembling and removing the syringe with respect to the holder.

Since the syringes illustrated in conjunction with the various embodiments herein shown and described may be the same, the reference numerals assigned to the syringe and its component parts in the description of the foregoing embodiment will be retained in the description of the several other embodiments shown in Figs. 12 through 20.

Referring now to the embodiment of the present invention illustrated in Figs. 12 and 13, the device there shown, like the previously described embodiment, has a barrel portion 70, an end portion 71 and a connecting shank portion 72. A cap or guard element 73 is associated with the end portion 71 as in the first described embodiment.

The syringe 14 is associated with the device as in the previous embodiment excepting that the flattened collar 20 is disposed in an annular enlargement 77 formed at the end of a sleeve 78 which is disposed within barrel portion 70. An end cap 80 for barrel portion 70 has an inwardly projecting sleeve 81 which gives sliding bearing support to the opposite end of sleeve 78. A cylindrical member 84 corresponding generally to operating member 35 of Figs. 1 through 11 is disposed for axial sliding movement in sleeve 78 and is otherwise the same as operating member 35. A compression coil spring 86 acts between end cap 80 and the remote end of wall portion 90 of operating member 84. A limit screw 93 performs the same function as rod 56 of the previous embodiment.

Fig. 12 shows the device in an intermediate position where the needle of the syringe has been projected but the contents of the syringe have not been fully expelled. In setting the device for operation, sleeve 78 is first moved to the right as viewed in Fig. 12. A pawl 95 has a leaf spring support 96 secured to sleeve 78 and leaf spring support 96 and pawl 95 are shown disposed in a slot 97 formed in barrel portion 70. Movement of sleeve 78 to the right as viewed in Fig. 12 cams spring support 96 downwardly as viewed in Fig. 12 and causes pawl 95 to pass through an opening 99 formed in sleeve 78 and into engagement with ratchet teeth 100 of operating member 84. The spring support 96 is biased to urge pawl 95 into engagement with teeth 100. During all but this first part of the movement of sleeve 78 to the right, operating member 84 moves with it.

A locking pawl 102 and an operating lever portion 103 thereof are the same in construction and operation as pawl 45 and release lever 50 of the previous embodiment. When sleeve 78 reaches its limit of movement to the right as viewed in Fig. 12, pawl 102 engages a notch 105 formed in sleeve 78 and retains sleeve 78 releasably in withdrawn position. Further setting of the holder involves manual movement of operating member 84 further to the right as viewed in Fig. 12 according to the dose to be administered. Sleeve 70 is provided with markings as in Fig. 1, the showing of the markings being omitted in the figures illustrating the present embodiment. As operating member 84 moves to the right relative to sleeve 78, pawl 95 cams idly along ratchet teeth 100 and operating member 84 is retained thereby in any adjusted right-hand position desired, as for instance when screw 107 of operating member 84 engages the end of adjusting screw 93.

The holder is then ready to receive the syringe and placement of the latter in the holder with the head of the syringe plunger in engagement with or close to the padded end of screw 107 of operating member 84 is accomplished just as in the case of the previous embodiment, and the needle of the syringe will automatically be disposed in withdrawn position as shown in Figs. 2 and 3 of the previous embodiment. Releasing of the device for operation is accomplished by release lever 103 in the same manner as previously set forth, and projection 110 thereof may be employed as a manual brake as previously described.

When sleeve 78 is released in this manner, spring 86 moves the sleeve and operating member 84 to the left as a unit through the cooperation of pawl 95 until the needle of the syringe is inserted in the patient, at which point the slanted nose portion of pawl 95 engages the left end of slot 87, which is likewise slanted, and pawl 95 is automatically cammed from engagement with ratchet teeth 100, against the resistance of spring support 86. This releases operating member 84 for movement relative to sleeve 78 and, under the impetus of spring 86, the operating member proceeds to the left until the plunger has expelled the entire contents of the syringe.

The embodiment illustrated in Figs. 14 through 17 will now be described. This form of the device is similar to the one shown in Figs. 1 through 11 in its manner of operation and differs mainly in the manner in which a syringe is retained in the holder and in the construction and arrangement of the body engaging guard element. Like the first-described embodiment, the present one has a barrel 115 with an end cap 116 and an offset shank 117 projecting therefrom at the other end. Shank 117 carries an angularly formed guard or foot element 118 which has a longitudinal slot (not shown), for engagement by a screw and nut assembly 120, whereby the foot 118 may be adjustably located lengthwise with respect to shank 117.

As appears from Fig. 16, the barrel portion 115, adjacent the plane on which Fig. 16 is taken, has a lateral opening 124 of the full width of the interior of the barrel. The syringe 14 need accordingly not be rotated in assembling the syringe. A spring element 125 fixed to shank 117 has a pair of longitudinally spaced U-shaped spring clip portions 126 and 127 which are so formed that they support the body of syringe 14 firmly but with a light enough pressure to permit endwise movement of the syringe for inserting the needle into the patient in a manner otherwise identical with that described in connection with the first embodiment.

In Figs. 17, the cylindrical operator is designated 130, and an abutment screw 131 carried by the end wall of the operating member has a rearwardly extending shank 133 which is accessible for adjusting the axial position of screw 131 when the cylindrical operator 130 is at a right-hand position, as in Fig. 17. Cap 116 of barrel 115 supports an inwardly extending tube 135 as by means of the bent-over flange portion 136 at the end of tube 135. The only remaining distinction between the embodiment of Figs. 14 through 17 and the first-described embodiment is found in the arrangement of calibrations along barrel 115. A longitudinal opening 138 is formed in barrel 115 with suitable scales provided along its edges so that the forward end of cylindrical operator 130, designated 139 in Fig. 14, indicates the ca-

pacity setting of the holder. The calibration arrangement of Fig. 14 may be employed with equal advantage in the first-described embodiment.

In the embodiment of Figs. 18 through 20 the device is arranged in such manner that it may be used for taking up doses in a syringe, as well as in the injection thereof into patients. Further, a syringe may, by the use of this form of holder, be employed in the extraction of blood specimens and the like from patients. The embodiment now to be described has the further advantage of being capable of withdrawing the needle from the patient without changing the initial position of the holder, the entire injecting operation being thus concluded with the holder in firm position against the patient's skin. For convenience of manipulation the embodiment about to be described is in the form of a pistol with a manually operable trigger for operating the syringe.

Referring to the administration of insulin by way of example, the following steps comprise the full administration procedure, so far as manipulation of the syringe is concerned. The plunger is first withdrawn to the desired dose to introduce an equivalent volume of air into the syringe. The needle of the syringe is then inserted through a rubber stopper which forms the cap of the insulin vial. The air in the syringe is then injected into the vial, the vial is inverted and the desired dose is drawn into the syringe by again withdrawing the plunger. The needle is then withdrawn from the vial and the syringe is ready for injecting the insulin by first inserting the needle into the patient, then operating the plunger to inject the dose, and finally withdrawing the needle from the patient.

Referring to Figs. 18 through 20, the form of a device there shown comprises a barrel portion 140, a shank 141 projecting from an end thereof, and a cylindrical end portion 142. The shank 141 and end portion 142 and the mode of introducing the syringe into the device may be the same as in the first described embodiment. However, collar 20 of syringe cylinder 16 is assembled in a transversely extending channel formation 145 by the quarter rotation of the syringe previously described. Channel formation 145, which serves as a part for gripping the syringe cylinder is integral with a longitudinally slotted channel shaped bar 147.

A rack member 150 of dove-tail formation, as shown in Fig. 20, is supported for longitudinal movement in a complementary groove 151 formed in barrel portion 140. At its end, rack 150 is provided with hook formations 152 and 153 which receive and grip the head 18 of the syringe plunger 17 when the syringe is assembled in the device. Rack 150 cooperates with the walls of barrel portion 140 to provide a longitudinal enclosure 155 within which bar 147 may slide longitudinally under certain conditions and in a manner which will presently appear.

Barrel portion 140 has a butt portion 160 whereby the device may be held in the manner of a pistol and a trigger element 161 forms part of a rack 162 which is guided for longitudinal sliding movement. The opposite end of rack 162 has secured thereto or formed therewith a spring pin 164 which projects into an opening in the end wall of barrel 140 and thus serves as a guide for rack 162. Rack 162 is further guided by a roller 166 supported for free rotation in the butt portion 160 and by meshing engagement with a pinion 168 which is rotatably mounted by means of a pin 170 supported at its opposite ends in bearing

portions 171 and 172 formed in barrel portion 140. Pinion 168 is fixed to or formed with a gear 174 which meshes with rack 150.

A compression coil spring 175 surrounds spring pin 164 between the end of rack 162 and the adjacent end wall of barrel portion 140 and it will be seen from the foregoing that, when no manual pressure is being exerted on trigger 161, spring 175 will urge rack 162 to the left as viewed in Fig. 18 and thus move rack 150 to the right to an extreme withdrawn position. This extreme position will be variably determined in a manner which will presently appear.

Slotted bar 147 has a bifurcated end portion 180 which pivotally supports a rock arm 181 which has latches 182 and 183 at its opposite ends. A spring element 184 secured at its opposite ends in bifurcation 180 acts against a pair of protuberances projecting from the hub portion of rock arm 181 to provide a snap over mechanism for rock arm 181 whereby it is spring urged to its spring illustrated position in Fig. 18 and is also spring urged to an opposite more clockwise position when manual pressure is exerted on latch portion 183, for reasons which will presently appear. Hook portion 153 of rack 150 has an upwardly projecting lug 188 for engagement by latch arm 183 when the rock arm 181 is in its opposite position from that illustrated in Fig. 18. It will be noted that the upper portion of barrel portion 140 is slotted as at 190 to receive bifurcation 180 and also to receive the head portion 192 of a screw 193 whose shank projects through the slot in bar 147 for engagement with a nut 194 disposed in the channel which comprises bar 147. The lower end of screw 193 projects downwardly into a groove 196 formed in the adjacent surface of bar 150. The screw 193 and the groove 196 form a lost-motion connection between the bar 147 and the rack or actuator 150, the element 193 of which is adjustable longitudinally of the trough 140, 141, 142 to vary the extent of the lost motion. Screw 193 supports a marking plate 197 as shown in Fig. 20 and a downward extension 198 of plate 197 prevents rotation of plate 197 when screw 193 is rotated. The opposite ends of plate 197 may be pointed as indicated in Fig. 19 to cooperate with a pair of scales 198 and 199 provided on the outer surface of barrel portion 140 for measuring insulin doses of either 20 or 40 unit strength, or any other material.

The manner in which the device of Figs. 18 through 20 is employed and its sequence of operations will now be described. Assuming that it is desired to administer a maximum dose, screw 193 is loosened, placed in the position illustrated in Figs. 18 and 19, and tightened to fix screw 193 and marker 197 relative to channel bar 147. When it is in the position illustrated in Fig. 18 latch 182 prevents any relative axial movement between the syringe cylinder and the holder proper. In Fig. 18 trigger or operating member 161 is shown in a maximum compressed position. The next step is to release trigger 161 which withdraws the plunger 17 of the syringe through the operation of rack 150 by the spring or operating member 175, until the bottom end of screw 193 engages the opposite end of groove 196 of rack 150. This movement takes into the syringe a quantity of air equivalent to the volume of the dose to be administered. Note that the longitudinal setting of screw 193 determines the amount of travel of rack 150 by reason of the initial distance between the left-hand end of groove 196 and end of screw 193.

After the syringe plunger is thus withdrawn the needle 19 is inserted into an insulin vial and trigger 161 is manually compressed until the plunger of the syringe is fully inserted, discharging the air from the syringe into the vial. The vial is then inverted and trigger 161 is released, which causes the syringe plunger to again be withdrawn by rack 150 and the dose taken up is again accurately determined by cooperation between screw 193 and the left-hand end of groove 196.

After the needle is removed from the vial rock arm 181 is manually oscillated in a clockwise direction to release latch 182 and the snapover action of spring 184 disposes latch 183 in position for operation in a manner which will presently appear. Release of latch 182 permits spring 175 to extend its operation by continued movement of rack 162, pinion 168, gear 174 and rack 150. This continued operation moves channel bar 147 to the right as viewed in Fig. 18, through engagement of the left end of groove 196 against screw 193, and the entire syringe is moved axially to the right as viewed in Fig. 18 until the right-hand end of channel bar 147 abuts against a bearing roller 200 journaled in barrel portion 140 for normally engaging against the back of rack 150.

This degree of withdrawing movement of the entire syringe is sufficient to dispose the needle 19 behind the extreme end of cylindrical end portion 142 in substantially the position illustrated in Figs. 2 and 3 of the first-described embodiment. The outer end of end portion 142 is then placed against the patient and the trigger 161 is manually compressed. Due to the dash pot action of the syringe the latter will first move bodily to project the needle into the patient until the left end of channel bar 147 reaches the left end wall of barrel portion 140.

Continued pressure upon trigger 161 moves the plunger into the syringe until the contents of the latter are fully expelled. At this juncture latch 183, which is then in an opposite position to that illustrated in Fig. 18, automatically cams over and latches behind lug 188 of rack 150. Release of pressure from trigger 161 then permits spring 175 to act and withdraw rack 150 to the right as viewed in Fig. 18 and, since channel bar 147 and rack 150 are now locked together by latch 183, the syringe with its plunger is withdrawn as a unit and the needle is thus withdrawn from the patient to entirely complete the administration of the dose.

What is claimed is:

1. Syringe means including a holder comprising a body member and a syringe having the usual needle at one end and a depressible expulsion plunger projecting from the other end, opposite ends of said syringe having opposed flattened portions, said body member having an end portion thereof engageable with a patient's skin and an opposite end portion including syringe plunger operating means, a connecting portion offset from the axis of the supported syringe whereby the syringe body is exposed to view and manipulation, said end portions including lateral openings having reduced entrance portions to receive the syringe across flats and permit partial rotation thereof for releasably retaining the syringe body in association with the holder, and means limiting lengthwise movement of the syringe relative to the holder between an initial position where the needle is behind the skin engaging means and a terminal position where the needle is beyond the skin engaging means a distance sufficient to

provide for proper entry of the needle into the patient's body.

2. Syringe means including a holder comprising a body member and a syringe having the usual needle at one end and a depressible expulsion plunger projecting from the other end, opposite ends of said syringe having opposed flattened portions, said body member having an end portion thereof engageable with a patient's skin and an opposite end portion including syringe plunger operating means, a connecting portion offset from the axis of the supported syringe whereby the syringe body is exposed to view and manipulation, said end portions including lateral openings having reduced entrance portions to receive the syringe across flats and permit partial rotation thereof for releasably retaining the syringe body in association with the holder.

3. A syringe for use with a cylindrical holder having reduced lateral entrance openings for receiving the syringe body, said syringe having a needle at one end and a manipulating plunger at its other end, said syringe having annular enlargements at its opposite ends with diametrically opposed aligned flats for introducing the syringe through the holder entrance openings and partially rotating the holder and syringe relative to each other to prevent inadvertent disassembly.

4. A syringe holder comprising a body member for supporting a syringe having the usual needle at one end and a depressible expulsion plunger projecting from the other end, said body member having an end portion thereof for receiving the needle end of the syringe and an opposite end portion including syringe plunger operating means, said first end portion having a cap screw threaded thereon for relative axial adjustment and engageable with a patient's skin to comprise a guard for the syringe needle, and means limiting lengthwise movement of the syringe relative to the holder between an initial position where the needle is behind the skin engaging cap and a terminal position where the needle is beyond the skin engaging cap a distance sufficient to provide for proper entry of the needle into the patient's body, said first end portion and said cap having lateral openings whereby they may be directly assembled in adjusted longitudinal position by direct lateral and partial rotational movement.

5. A device for operating a hypodermic syringe having a cylinder, a plunger projecting from the rear end thereof, and a needle at the front end of the cylinder; the device comprising a holder having an elongated stationary trough for engaging and supporting the syringe cylinder and forming a guide for longitudinal movement of the cylinder along the trough, the space between the trough edges being sufficiently wide to receive the syringe, an actuator in the trough movable therealong in engagement with the syringe plunger, thereby sliding the cylinder forward along the trough to project the needle, and a stop on the holder for limiting said forward sliding of the cylinder by the actuator, to cause the plunger to be moved in the cylinder by continued movement of the actuator.

6. A device according to claim 5, comprising also a spring mounted in the holder to the rear of the trough and acting upon the actuator to operate it.

7. A device according to claim 5, in combination with the syringe, the syringe cylinder being rotatable in the trough and having diametrically opposed flats providing the cylinder with a generally rectangular cross-section, the smaller di-

mension of the rectangular cross-section being less than the width of the space between the trough edges, and the larger dimension of the rectangular cross-section being greater than said width.

5 8. A device according to claim 5, comprising also a restraining member in the trough made of resilient material shaped for sliding frictional engagement with the periphery of the syringe cylinder to hold it against accidental longitudinal movement in the trough.

10 9. A device according to claim 5, comprising also a second stop in the holder located to the rear of the actuator and engageable thereby to limit movement of the actuator away from the trough, and an adjustment member connected to the second stop for adjusting it longitudinally of the trough.

15 10. A device according to claim 5, comprising also a member movably mounted on the holder and having a catch engageable with the actuator to retain it in a retracted position, the catch being movable by the member to release the actuator, said member also having a brake engageable with the actuator by movement of the member to release the catch.

20 11. A device according to claim 5, comprising also a bar movable longitudinally of the trough and having a part for gripping the syringe cylinder, the actuator having a part for gripping the syringe plunger, a latch for releasably securing the bar to the holder to prevent said longitudinal movement of the bar, the latch being movable to a released position for releasing the bar from the holder, an operating member connected to the actuator for moving it rearward in the holder, the bar having a part engageable by the actuator to limit said rearward movement, the actuator having an element engageable with the bar to project it forward upon forward movement of the actuator, and a second operating member connected to the actuator for pressing it forward.

25 12. A device according to claim 11, in which the latch is mounted on the bar, the actuator having a part engageable by the latch in its released position to couple the bar to the actuator.

30 13. A device according to claim 5, comprising also a pistol grip projecting laterally from the holder in fixed relation to the trough, a trigger disposed forwardly of the grip and movable thereto, and an operative connection between the trigger and the actuator.

35 14. A device according to claim 5, comprising also a bar movable longitudinally of the trough and having a part for gripping the syringe cylinder, the actuator having a part for gripping the syringe plunger, and a lost-motion connection between the bar and the actuator for moving the bar rearward with the actuator.

40 15. A device according to claim 5, comprising also a bar movable longitudinally of the trough and having a part for gripping the syringe cylinder, the actuator having a part for gripping the syringe plunger, and a lost-motion connection between the bar and the actuator for moving the bar rearward with the actuator and including an element adjustable longitudinally of the trough relative to the bar to vary the extent of the lost motion.

45 16. A device according to claim 5, comprising also a bar movable longitudinally of the trough and having a part for gripping the syringe cylinder, the actuator having a part for gripping the syringe plunger, a lost-motion connection

50 75

13

between the bar and the actuator for moving the bar rearward with the actuator, and a stop for limiting rearward movement of the bar relative to the trough.

17. A device according to claim 5, comprising also a bar movable longitudinally of the trough and having a part for gripping the syringe cylinder, the actuator having a part for gripping the syringe plunger, a lost-motion connection between the bar and the actuator for moving the bar rearward with the actuator, and a releasable latch operable selectively to couple the bar to the holder or to the actuator.

18. A device according to claim 5, comprising also a bar movable longitudinally of the trough and having a part for gripping the syringe cylinder, the actuator having a part for gripping the syringe plunger, a lost-motion connection between the bar and the actuator for moving the bar rearward with the actuator, a latch on
